DRUM ASSEMBLY.

Application filed May 12, 1927. Serial No. 190,949.

This invention relates to drum assemblies and more particularly to a drum assembly for use in connection with the draw-works of well drilling apparatus.

- 5 Changes in conditions in well drilling have brought to light the fact that the ordinary drum structure previously employed in the draw-works of well drilling apparatus is inefficient and dangerous when employed 10 with the present day deep well drilling apparatus and attempts to modernize this ordinary drum structure and adapt the same for use with deep well drilling apparatus have so weakened the drum structure that it becomes dangerous. These drum structures, as ordinarily manufactured, are furthermore difficult to apply to the draw-works shaft and when applied, demand an excessive space on the draw-works shaft, due to the fact that 15 20 the keys which hold the drum in position upon the shaft must be driven from the outer ends of the drums and accordingly keyways must be provided, which extend beyond the outer end of the drum hub. This 25 provides a roughened shaft surface, which inhibits compactness, in that at opposite ends of the drum of the draw-works apparatus, there are arranged upon the shaft, elements which have rotation with relation to 30 the shaft, so that these roughened shaft surfaces would tend to destroy the same. Furthermore, it has been found necessary in new 35 drum structures to employ means for water-cooling the flanges of the drums, due to the fact that these drums heat excessively through their operation against the brakes when lowering heavy loads through long distances, as required in present day drilling apparatus. The combination of keyways 40 and bores formed in the shaft for the passage of water has a tendency to weaken the shaft, so that this shaft must be made of much greater size if a proper safety factor is to be preserved. Accordingly, an important 45 object of this invention is to provide a drum construction, such that the keyway slots for the securing keys may be positioned inwardly of the ends of the drum and accordingly permit the drum structure to be 50 as compactly arranged as possible for the size drum employed and which will permit of the use of water-cooled flanges upon the drum without the formation of coinciding water passages and keyways, which would

weaken the shaft structure and necessitate the use of a larger shaft.

A further object of the invention is to provide a device of this character, in which the drum structure is such that the problem of circulating the cooling fluid and assembling the drum upon the shaft is greatly simplified.

These and other objects I attain by the construction shown in the accompanying drawings, wherein for the purpose of illustration is shown a preferred embodiment of my invention and wherein:

Figure 1 is an enlarged fragmentary sectional view through the drum shaft of a draw-works having a drum applied thereto in accordance with my invention;

Figure 2 is a similar view showing the manner of setting the keys of the drum structure when positioned upon the shaft;

Figure 3 is a section on the line 3-3 of Figure 2;

Figure 4 is a section on the line 4-4 of Figure 2.

Referring now more particularly to the drawings, the drum is formed in two sections 10 and 11, each having a hub portion 12 and a brake flange 13, which projects beyond the outer face of the outer end of its hub. These brake flanges provide an annular water circulation space 14. The inner end of the drum section 11 is provided with an extension 15 having a tapered outer face 16, which engages with a correspondingly tapered face formed upon the inner end of the drum section 10, which seats against the end of the section 11 proper and combines therewith to provide a continuous smooth drum surface. The inner face of the drum sections have projecting inwardly therefrom radially extending reinforcing ribs 17, which are circumferentially spaced. The hub of each drum section is formed with a pair of keyways 18 spaced apart 90° and adapted for the reception of tapered keys 19 inserted from the inner end of the hub. Each hub section is furthermore provided with openings 20, preferably four in number and uniformly spaced and two of the openings of each hub structure align with the keyways of the opposite hub when the drum is assembled. The extension 15 has an inwardly directed flange 21 having openings 22 corresponding in number and arrangement to

the openings 20 of its hub formed therethrough

The shaft 23 is provided with keyways 24, for the reception of the keys 19, the outer ends of which are spaced apart a distance less than the distance between the outer ends of the hubs when the sections of the drum are in assembled relation and the inner ends of which extend inwardly of the inner ends 10 of these hubs. Bores 25 extend inwardly from the ends of the shaft 23 and terminate outwardly of the ends of the keyways. The shaft is provided upon its exterior from a point immediately outwardly of the ends 15 of the keyways with threaded portions 26.

In assembling the drum upon the shaft, the keys are placed in position and the drum sections pressed upon the shaft are properly engaged with these keys. After the drum 20 sections have been properly placed and the tapered extension 15 is fully engaged in the end of the section 10, collars 27 are screwed upon the threaded portions 26, so that they abut the outer ends of the hub 12. 25 These collars are of such width that they do not project beyond the outer faces of the brake flanges 13 a distance greater than is absolutely necessary for clearance and the inner faces of these collars are formed with 30 annular grooves 28, which are in communication with the associated bore 25 of the shaft through a radial port 29. The annular groove of the inner face of each collar 27 communicates with a conduit 30 carried 35 by the collar and adapted to be coupled, as at 31, with an inlet conduit 32 communicating with the water space 14 of the associated brake flange 13. After the drums are seated in position and the collars placed, the keys 40 19 are firmly seated by inserting a drift 33 through the openings 20 and 21 and driving it against the ends of the keys. When the keys have been fully seated, a connection is made between the water spaces by 45 inserting a conduit 34 through aligned openings 20 and 22 and connecting the same, as at 35, with conduits 36 communicating with the water spaces 14 at points diametrically opposed to the conduits 32.

50 It will be obvious that by employing a structure of this character, the drum is not only capable of being more conveniently and compactly applied to the shaft 23, but may be much more readily handled, since the 55 weight of these sections will be considerably less than that of the ordinary drum structure which is shipped as a unit. The operation of pressing the sections upon the drum will be much easier than that of applying 60 the ordinary drum, and at the same time, a very convenient and efficient method of providing water circulation is provided without weakening the shaft 23 to the extent that is ordinarily necessary.

55 Since the construction hereinbefore set

forth is capable of a certain range of change and modification without materially departing from the spirit of the invention, I do not limit myself to such specific structure except as hereinafter claimed.

70

I claim:—

1. In a drum mounting for draw works and in combination, a shaft, a drum formed in two sections each including a hub, said sections assembled by relative movement 75 thereof longitudinally of the shaft, coacting keyways in the shaft and said hub portions, keys therein, the keyways of the shaft having their outer ends inwardly of the ends of the drum when the sections thereof are 80 in assembled relation upon the shaft and openings permitting driving access to the inner ends of said keys.

2. In a drum mounting for draw works and in combination, a shaft, a drum formed 85 in two sections each including a hub, said sections assembled by relative movement thereof longitudinally of the shaft, coacting keyways in the shaft and said hub portions, keys therein, the keyways of the shaft 90 having their outer ends inwardly of the ends of the drum when the sections thereof are in assembled relation upon the shaft and openings permitting driving access to the inner ends of said keys and means upon the 95 shaft abutting the outer end faces of the hub sections for retaining said hub sections in assembled relation.

3. In a drum mounting for draw works and in combination, a shaft, a drum formed 100 in two sections each including a hub, said sections assembled by relative movement thereof longitudinally of the shaft, coacting keyways in the shaft and said hub portions, keys therein, the keyways of the shaft 105 having their outer ends inwardly of the ends of the drum when the sections thereof are in assembled relation upon the shaft and openings in each hub portion permitting driving access to the inner ends of the keys of 110 the other of the hubs to seat the same.

4. In a drum mounting for draw works and in combination, a shaft, a drum formed 115 in two sections each including a hub, said sections assembled by relative movement thereof longitudinally of the shaft, coacting keyways in the shaft and said hub portions, keys therein, the keyways of the shaft having their outer ends inwardly of the ends 120 of the drum when the sections thereof are in assembled relation upon the shaft and openings permitting driving access to the inner ends of said keys, said drum sections including portions telescopically engaging 125 in the assembly thereof, the male element of the telescopic engagement having an inwardly extending flange for engagement with the shaft.

5. In a drum mounting for draw works 130 and in combination, a shaft, a drum formed

- in two sections each including a hub, said sections assembled by relative movement thereof longitudinally of the shaft, coacting keyways in the shaft and said hub portions, 5 the keyways of the shaft having their outer ends inwardly of the ends of the drum when the sections thereof are in assembled relation upon the shaft, said drum sections including portions telescopically engaging in the 10 assembly thereof, the male element of the telescopic engagement having an inwardly extending flange for engagement with the shaft.
6. In a drum mounting for draw works 15 and in combination, a shaft, a drum formed in two sections each including a hub, said sections assembled by relative movement thereof longitudinally of the shaft, coacting keyways in the shaft and said hub portions, 20 the keyways of the shaft having their outer ends inwardly of the ends of the drum when the sections thereof are in assembled relation upon the shaft, said drum sections including portions telescopically engaging in the 25 assembly thereof, the male element of the telescopic engagement having an inwardly extending flange for engagement with the shaft, openings in said flange aligning with the keyways of the hubs, each hub having 30 openings therein aligning with the keyways of the other hub and permitting access to the inner ends of keys positioned therein to seat the same.
7. In a drum mounting for draw works 35 and in combination, a shaft, a drum formed in two sections each including a hub, said sections assembled by relative movement thereof longitudinally of the shaft, coacting keyways in the shaft and said hub portions, 40 the keyways of the shaft having their outer ends inwardly of the ends of the drum when the sections thereof are in assembled relation upon the shaft, said drum sections including portions telescopically engaging in the 45 assembly thereof, the male element of the telescopic engagement having an inwardly extending flange for engagement with the shaft, and threaded collars upon the shaft 50 engaging the outer ends of the hubs preventing separation thereof.
8. In a drum mounting for draw works and in combination, a shaft, a drum formed in two sections each including a hub, said sections assembled by relative movement 55 thereof longitudinally of the shaft, coacting keyways in the shaft and said hub portions, the keyways of the shaft having their outer ends inwardly of the ends of the drum when the sections thereof are in assembled relation upon the shaft, said drum sections including portions telescopically engaging in the 60 assembly thereof, the male element of the telescopic engagement having an inwardly extending flange for engagement with the shaft, openings in said flange aligning with the keyways of the hubs, each hub having 65 openings therein aligning with the keyways of the other hub and permitting access to the inner ends of keys positioned therein to seat the same, threaded collars upon the shaft engaging the outer ends of the hubs preventing separation thereof, said shaft outwardly of 70 the keyways being provided with a bore, the collars having grooves in communication with their respective bores through radial ports, opposite ends of the drum sections having brake flanges each including an annular water cooling chamber, means connecting the groove of each collar with the water chamber of the associated flanges and a connection between said water chamber.
9. In a drum mounting for draw works and in combination, a shaft, a drum formed in two sections each including a hub, said sections assembled by relative movement thereof longitudinally of the shaft, coacting keyways in the shaft and said hub portions, the keyways of the shaft having their outer ends inwardly of the ends of the drum when the sections thereof are in assembled relation upon the shaft, said drum sections including portions telescopically engaging in the 85 assembly thereof, the male element of the telescopic engagement having an inwardly extending flange for engagement with the shaft, openings in said flange aligning with the keyways of the hubs, each hub having 90 openings therein aligning with the keyways of the other hub and permitting access to the inner ends of keys positioned therein to seat the same, threaded collars upon the shaft engaging the outer ends of the hubs preventing separation thereof, said shaft outwardly of 95 the keyways being provided with a bore, the collars having grooves in communication with their respective bores through radial ports, opposite ends of the drum sections having brake flanges each including an annular water cooling chamber, means connecting the groove of each collar with the water chamber of the associated flanges and a connection between said water chamber.
10. In a drum mounting for draw works and in combination, a shaft, a drum formed in two sections each including a hub, said sections assembled by relative movement thereof longitudinally of the shaft, coacting keyways in the shaft and said hub portions, the keyways of the shaft having their outer ends inwardly of the ends of the drum when the sections thereof are in assembled relation upon the shaft, said drum sections including portions telescopically engaging in the 110 assembly thereof, the male element of the telescopic engagement having an inwardly extending flange for engagement with the shaft, openings in said flange aligning with the keyways of the hubs, each hub having 115 openings therein aligning with the keyways of the other hub and permitting access to the inner ends of keys positioned therein to seat the same, threaded collars upon the shaft engaging the outer ends of the hubs preventing separation thereof, said shaft outwardly of 120 the keyways being provided with a bore, the collars having grooves in communication with their respective bores through radial ports, opposite ends of the drum sections having brake flanges each including an annular water cooling chamber, means connecting the groove of each collar with the water chamber of the associated flanges and a connection between said water chamber.
11. In a drum mounting for draw works and in combination, a shaft, a drum formed in two sections each including a hub, said sections assembled by relative movement thereof longitudinally of the shaft, coacting keyways in the shaft and said hub portions, the keyways of the shaft having their outer ends inwardly of the ends of the drum when the sections thereof are in assembled relation upon the shaft, said drum sections including portions telescopically engaging in the 125 assembly thereof, the male element of the telescopic engagement having an inwardly extending flange for engagement with the shaft, openings in said flange aligning with the keyways of the hubs, each hub having 130 openings therein aligning with the keyways of the other hub and permitting access to the inner ends of keys positioned therein to seat the same, threaded collars upon the shaft engaging the outer ends of the hubs preventing separation thereof, said shaft outwardly of the keyways being provided with a bore, the collars having grooves in communication with their respective bores through radial ports, opposite ends of the drum sections having brake flanges each including an annular water cooling chamber, means connecting the groove of each collar with the water chamber of the associated flanges and a connection between said water chamber.

nular water cooling chamber, means for connecting the groove of each collar with the water chamber of the associated flanges and a connection between said water chamber, 5 extending through the aligned opening of the hubs and flange.

11. In a drum mounting for draw works and in combination, a shaft, a drum formed in two sections each including a hub, said 10 sections assembled by relative movement thereof longitudinally of the shaft, coacting keyways in the shaft and said hub portions, keys therein, the keyways of the shaft having their outer ends inwardly of the ends of 15 the drum when the sections thereof are in assembled relation upon the shaft and openings in each of said hubs permitting driving access to the inner ends of the keys associated with the other of the hubs.

12. In a drum mounting for draw works 20 and in combination, a shaft, a drum upon the shaft having hub portions at its opposite ends and having a hollow brake flange, co-acting keyways in the shaft and said hub portions, keys therein, the keyways of the 25 shaft having their outer ends inwardly of the ends of the hub portions, the hub portions having openings permitting driving access to the inner ends of the keys and means for conducting water to the hollow brake 30 flange including bores in the shaft outwardly of the ends of the drum, a conduit extending through the drum at the openings thereof and connections between said conduit and the bores including the hollow brake flange. 35

In testimony whereof I affix my signature.

LEE J. BLACK.
